(57) **CLAIM**

The ornamental design for an oral irrigator as shown and described.

DESCRIPTION

FIG. 1 is a front view of an oral irrigator, shown with the reservoir of the oral irrigator in a closed position, showing my new design;

FIG. 2 is a back view thereof;

FIG. 3 is a left side view thereof;

FIG. 4 is a right side view thereof;

FIG. 5 is a top view thereof;

FIG. 6 is a bottom view thereof;

FIG. 7 is a front left top perspective view thereof; and,

FIG. 8 is a front right top perspective view thereof, shown with the reservoir of the oral irrigator in an open position. The broken lines depict portions of the oral irrigator that form no part of the claimed design.

1 Claim, 8 Drawing Sheets
